UNITED STATES PATENT OFFICE.

BENJAMIN FRANKLIN DAVIES, OF WEST HOBOKEN, NEW JERSEY,
ASSIGNOR TO L. STRAUS & SONS, OF NEW YORK, N. Y.

DESIGN FOR A GLASS VESSEL.

No. 37,999.

Specification for Design.

Patented May 8, 1906.

Application filed March 15, 1906. Serial No. 306,303. Term of patent 7 years.

To all whom it may concern:

Be it known that I, BENJAMIN FRANKLIN DAVIES, a citizen of the United States, residing in the city of West Hoboken, Hudson county, and State of New Jersey, have invented a new, original, and ornamental Design for Glass Vessels, of which the following is a specification.

In the accompanying drawings, Figures 1

and 2 are side elevations, and Fig. 3 is a plan view.

I claim—

The ornamental design, as herein shown, for a glass vessel.

BENJAMIN FRANKLIN DAVIES.
